CLAIM

The ornamental design for a chair, as shown and described.

DESCRIPTION

FIG. 1 is a perspective view of a chair embodying the present invention;

FIG. 2 is a front view of FIG. 1;

FIG. 3 is a right side view of FIG. 1, the left side view being a mirror image of the right side;

FIG. 4 is a rear view of FIG. 1; and

FIG. 5 is a top view of FIG. 1.

FIG. 6 is a perspective view of another chair construction embodying the present invention;

FIG. 7 is a front view of FIG. 6;

FIG. 8 is a right side view of FIG. 6, the left side being a mirror image of the right side;

FIG. 9 is a rear view of FIG. 6; and,

FIG. 10 is a top view of FIG. 6.

The broken lines which form the boundary between claimed and unclaimed subject matter as well as the broken lines showing environment form no part of the claimed design
